UNITED STATES PATENT OFFICE.

CYRUS E. HANON, OF ST. LOUIS, MISSOURI.

DESIGN FOR A LIGHT-REFLECTING LENS AND PRISM FOR ILLUMINATED SIGNS.

41,094.

Specification for Design.

Patented Jan. 17, 1911.

Application filed October 20, 1910. Serial No. 588,222. Term of patent 7 years.

To all whom it may concern:

Be it known that I, CYRUS E. HANON, citizen of the United States, residing at St. Louis, State of Missouri, have invented a new, original, and ornamental Design for Light-Reflecting Lenses and Prisms for Illuminated Signs, of which the following is a specification, reference being had to the accompanying drawings, forming a part hereof.

In the drawings, Figure 1 is a side view of a light reflecting lens and prism to be disposed along the outline of a design, let-

ter, number, or other symbol entering as a component of the reading or other matter of an illuminated sign; and Fig. 2 is a face view of the same.

I claim:

The ornamental design for a light-reflecting lens and prism for illuminated signs, as shown.

CYRUS E. HANON.
